UNITED STATES PATENT OFFICE.

ROBERT Y. BARROWS, OF RUTHERFORD, NEW JERSEY, AND HAROLD P. CURTIS, OF NEW YORK, N. Y., ASSIGNEES TO ROBERT Y. BARROWS, INC., A CORPORATION OF NEW YORK.

SOUND BOX.

Application filed April 30, 1921. Serial No. 465,930.

The invention relates to improvements in sound boxes for talking machines and the like and the main object of the invention is to provide a sound box which is extremely sensitive and will more efficiently and accurately reproduce the desired sounds. Further and more specific objects, features and advantages will more clearly appear from the detail description given below taken in connection with the accompanying sheet of drawings which form a part of this specification.

In the drawings, Fig. 1 is a face view of a sound box embodying our invention in a preferred form thereof, certain parts being broken away in order to more clearly illustrate the construction. Fig. 2 is a vertical section taken on the line 2—2 of Fig. 1. Fig. 3 is a horizontal section taken on the line 3—3 of Fig. 1. Fig. 4 is a detail view illustrating a modification.

Referring to Figs. 1, 2 and 3, there is shown a sound box having a suitable framework 4 suitably recessed to receive a diaphragm 5 with rubber rings 6 and 7 arranged around the periphery of the diaphragm. In order to hold the diaphragm and rings 6 and 7 firmly in operative position in the sound box there is provided a bezel extending over the face of the diaphragm, said bezel having a flange 9 engaging the framework in a plane parallel to the plane of the diaphragm and having a circular cylindrical rim 10 extending outwardly and a flange 11 extending inwardly from the outer edge of said rim in a plane parallel to the plane of said diaphragm in order to more fully protect the diaphragm. On the other side the sound box is provided with a suitable tubular member 12 adapted to be connected to the tone arm of the talking machine or similar instrument in a manner well understood by those skilled in the art. The bezel 9, 10 and 11 is rigidly secured to the framework 4 by screws 13. Secured to the underneath side of the framework 4 by screws 14 is a member 15 having screw threaded therein and extending upwardly two conical pointed bearing members 16 and 17. 18 represents a stylus bar provided with conical recesses 19 and 20 against the bottom of which the conical pointed members 16 and 17 respectively bear. The

stylus bar is also provided with a conical recess 21 against the bottom of which bears 55 the point of a conical pointed bearing member 22, the bearing member 22 being resiliently forced into the conical recess 21 by means of a leaf spring 23 situated in a recess 24 in a framework 4. The points of the 60 conical members 16, 17 and 22 and the bottoms of the conical recesses 19, 20 and 21 all lie in a single line forming a pivotal axis about which a stylus bar 18 is adapted to oscillate and said line and pivotal axis 65 also lies in the plane of the diaphragm 5. The stylus bar 18 is curved outwardly at 25 and passes up through a cutaway opening in the rim 10 of the bezel and at its upper end is bent inwardly and rigidly secured to the 70 diaphragm 5 by screw 26. The stylus bar is provided with a needle recess 27 at its lower end into which the usual needle may be secured by screw 28. The spring 23 is slid- 75 able in recess 24 laterally, i. e., in a plane at right angles to the plane of the dia- phragm 5 and is likewise free to move over the top of the conical bearing member 22 so that the parts in this respect are made self-adjusting. 80

It will be seen from the above that there are provided three bearings for pivotally supporting the stylus bar, said bearings having all their bearing points in a single line in the plane of the diaphragm, each 85 of said bearings comprising a conical pointed member engaging the bottom of a conical pointed recess, one of the bearings comprising a spring pressed member resiliently holding the other bearing members in opera- 90 tive position. By having at least one of the bearings a conical pointed member having its point bearing against the bottom of a cooperative conical recess, lateral movement of the stylus bar in a line at right angles 95 thereto and in the plane of the diaphragm is prevented. Another of the conical bearing members engaging a cooperative re- cess prevents rotation of the stylus bar about the first mentioned bearing point 100 in a plane at right angles to the plane in which the stylus bar vibrates. By hav- ing the bearing points all in a single line the bearings for the stylus bar are practical- 105 ly frictionless. As the stylus bar operates there is no rubbing of surfaces anywhere

as the only points of contact between the stylus bar and its supporting bearing members are three points lying in the pivotal axis of the stylus bar. The stylus bar simply rocks about these three points and there is no relative motion between the conical points of the bearing members and the bottom of the conical recesses. By this arrangement the forces acting to operate the stylus bar do not have any friction to overcome and also there is no spring pressure to be overcome by such forces in oscillating the stylus bar and hence the stylus bar is made extremely sensitive and capable of more accurately reproducing the recorded sounds.

Referring to Fig. 4, we there show a modified arrangement in which the conical pointed bearing member 16 engaging the bottom of the conical recess 19 prevents lateral movement of the stylus bar in a line at right angles to the stylus bar in the plane of the diaphragm while the conical bearing member 17 engages the bottom of a V shaped groove 30 in the stylus bar which prevents rotation of the stylus bar in a plane at right angles to the diaphragm and stylus bar and about the point 16 as an axis. The leaf spring 23 forces a member 31 provided with a knife edge so that it bears down into a V shaped groove 32 and thereby holds the stylus bar with the recesses 19 and 30 into operative engagement with the conical bearing members 16 and 17. In the form shown in this figure as well as in the form shown in Figs. 1, 2 and 3 all of the recesses have their sides arranged at sufficiently great inclination so that the sides of the bearing members will not contact therewith during the oscillation of the stylus bar and the conical or knife edge bearing members will engage the recesses only at points in the actual line about which the stylus bar is pivoted. In Fig. 4 the bottom of the conical recess 19 and the bottom of the V-shaped recesses 30 and 32 all lie in a single line in the axis about which the stylus bar 18 is pivoted. The knife edge member 31 is provided with a flat top portion 33 adapted to bear against the leaf spring 23 but free to move laterally thereover. It will, therefore, appear that it is not necessary that all of the bearings for the stylus bar be comprised of a conical pointed bearing member engaging the bottom of a conical recess, but it is important that one of the bearings be so arranged in order to take up lateral thrust of the stylus bar.

Also although the invention has been described in great detail and with respect to preferred forms thereof, it is not desired that the invention be limited to such details and forms since many changes and modifications may be made and the invention embodied in other widely different forms with-

out departing from the spirit and scope thereof in its broader aspects.

We claim—

1. A sound box having a diaphragm, a cooperating stylus bar, and three bearings for pivotally supporting the stylus bar, said bearings having their bearing points all in a single line, one of said bearings comprising a conical pointed member engaging the bottom of a conical recess and a spring engaging one of said bearing members for resiliently holding the bearing members in operative position with the bearing points all in the axis about which the stylus bar is adapted to oscillate, said spring being slideable in a plane at right angles to the direction in which it exerts its spring pressure. 70

2. A sound box having a diaphragm, a cooperating stylus bar, and three bearings for pivotally supporting the stylus bar, said bearings having their bearing points all in a single line, and each of said bearings comprising a conical bearing member, one engaging the bottom of a conical recess and a spring engaging one of said bearing members for resiliently holding the bearing members in operative position with the bearing points all in the axis about which the stylus bar is adapted to oscillate, said spring being slideable in a plane at right angles to the direction in which it exerts its spring pressure, 80 and slideable in the same plane with respect to the conical bearing member which it engages. 85

3. In a sound box having a diaphragm, a cooperating stylus bar, bearing members for pivotally supporting said bar, one of said bearing members being disposed intermediate other bearing members on the opposite side of the bar, and a spring engaging one of said bearing members for resiliently holding said bar between said bearing members, said spring being slideable in a plane at right angles to the direction in which it exerts its spring pressure. 100

4. In a sound box having a diaphragm, a cooperating stylus bar, bearing members for pivotally supporting said bar, one of said bearing members being disposed intermediate the bearing members on the opposite side of the bar, and a spring engaging one of said bearing members and an adjacent portion of the sound box for resiliently holding said bar between said bearing members, said spring being slideable both with respect to the sound box and the engaged bearing member, transversely with respect to the direction in which it exerts its spring pressure. 105

5. In a sound box having a diaphragm, a cooperating stylus bar, conical bearing members engaging in conical depressions for pivotally supporting said bar, one of said bearing members being disposed intermediate the other bearing members on the oppo- 125

130

- site side of the bar, and a spring engaging said intermediate bearing member for resiliently holding the same against said bar, said spring being slidable at right angles to the direction in which it exerts its pressure. 5
6. In a sound box having a diaphragm, a cooperating stylus bar, conical bearing members for pivotally supporting said bar, one of said bearing members being disposed 10 intermediate the other bearing members on the opposite side of the bar, and a spring engaging said intermediate bearing member and an adjacent portion of the sound box for resiliently holding said bar against the other bearing members, said spring being 15 slidable both with respect to the sound box and the engaged bearing member transversely of the direction in which it exerts its pressure. 20
7. In a sound box having a diaphragm and a recess, a cooperating stylus bar, bearing members for pivotally supporting said bar, one of said bearing members being disposed intermediate other bearing members 25 on the opposite side of the bar, and a spring engaging one of said bearing members for resiliently holding said bar between said bearing members, said spring being slidable in the recess of the sound box.
8. In a sound box having a diaphragm 30 and recess, a cooperating stylus bar, bearing members for pivotally supporting said bar, one of said bearing members being disposed intermediate the bearing members on the opposite side of the bar, and a spring 35 engaging one of said bearing members and an adjacent portion of the sound box in the recess therein for resiliently holding said bar between said bearing members, said spring being slidable both with respect to 40 the sound box and the engaged bearing member.

Signed at New York city, in the county of New York, and State of New York, this 27th day of April, A. D. 1921.
